UNITED STATES PATENT OFFICE.

ELBERT T. BAILY, OF MOUNT KISCO, NEW YORK.

INSULATOR PIN AND BRACKET.

SPECIFICATION forming part of Letters Patent No. 701,246, dated May 27, 1902.

Application filed March 25, 1902. Serial No. 99,933. (No model.)

To all whom it may concern:

Be it known that I, ELBERT T. BAILY, a citizen of the United States, residing at Mount Kisco, in the county of Westchester and State 5 of New York, have invented certain new and useful Improvements in Insulator Pins and Brackets; and I do hereby declare the following to be a full, clear, and exact description of the invention, such as will enable others 10 skilled in the art to which it appertains to make and use the same.

My invention relates to an improvement in insulator-pins and is embodied in the construction and arrangement of parts presently 15 to be described, and defined in the claims.

The invention relates more particularly to that class of devices—such as pins, brackets, or pegs—for supporting and carrying conductors, such as overhead conductors, and it 20 is designed more particularly for use in connection with cross arms or poles or other supports; and the object of the invention is to provide a pin which can be quickly adjusted and applied, one wherein metal can be employed 25 in its construction, a pin or carrier which will securely hold the insulator against accidental movement or escape, which can be cheaply manufactured, and which in its application will avoid the necessity of boring or 30 drilling the supporting member to which the same is attached.

Other objects and features of the invention will presently be stated.

In the accompanying drawings I have 35 shown a preferred form and modification of the invention; but it is to be understood that the general principle and nature of the invention can be applied in various ways and with various forms of construction other than 40 those shown.

Figure 1 is an elevation of the cross-arm of a supporting-pole, showing the improved pin thereon. Fig. 2 is a side elevation of the same. Fig. 3 is a detailed section through 45 the yielding supporting-arms of the pin. Figs. 4, 5, and 6 are modified forms of the construction shown in Fig. 1. Fig. 7 illustrates a modified form of the invention, the same being in the form of a bracket or attachment to the side of the support.

A designates a cross-arm of a supporting-

post, which is constructed conveniently with a longitudinal channel B therein.

C C' designate two independent pin-sections arranged and fashioned so that when 55 in proper relation they constitute the pin. These members C and C' are conveniently constructed of metal, having the lower angular portions c with upturned ends fitted in the groove B. The portions c are connected to 60 the vertical portions c', which are extended upward and bent inward obliquely and thence upward at an oblique angle, forming thereby spring or yielding extensions c³. The extensions c³ carry on their upper ends semicylindrical threaded insulating-blocks c⁴, the threads being on the outer face only, while the inner faces fit the sides of the extensions. To secure the blocks in place, recesses e are formed near their upper ends, into which the 70 turned-over ends e² of the extensions fit. Other means may, however, be employed for that purpose. Between the extensions may be placed a wood or insulated filler-strip c⁵, (see Fig. 6,) which has a threaded edge corresponding 75 with the threads of the blocks c⁴. D designates the insulator, of a well-known form and construction, screw-threaded on the threaded portions of the pin.

The construction above described is such 80 that by embracing the sides of the arm A closely the upper ends of the pin will be separated and by securing the insulator thereonto the parts will be drawn close together, and owing to the yielding spring nature of the 85 material of which the pin members or sections are constructed there will be a constant binding tendency between the insulator and the pin, thus serving to firmly hold the insulator in place. To add to the rigidity or 90 strength of the upper portions of the pin, suitable braces c⁶ are formed along the outer faces of the oblique portions. These braces may be secured to the metal of the pins, but preferably are formed by rolling or striking 95 up the metal of the pins between the edges, forming thereby crimps or strengthening bends. To adjust the pin on the arm A, it is only necessary to place the different members thereof in position and then clamp them 100 in position by screwing on the insulator. It may, however, be found convenient in some

cases to pass screws or nails, such as E, through the upright portions of the pin members into the arm A.

A modification of the construction above described is illustrated in Figs. 4, 5, and 6. In the former the pin is constructed of a single band C², spanning the bottom of the arm, as shown at F. In Fig. 5 the pin members are similar to those shown in Fig. 1, except the channel in the arm A is omitted and the struck-up ends of the lower portions are in the form of brads or teeth, which penetrate the material of the arm. In Fig. 6 I have shown a construction whereby the members of the pin are constructed without the lower angular portions, the bent-in ends taking into the longitudinal grooves h in the sides of the arm A. In this connection I have found it convenient in some cases to substitute for the threaded wooden blocks of the pin metallic structures, as G, the same being formed of concavo-convexed extensions of the upper portions of the pin, their outer faces being threaded. An interposed wood filler C⁵ may be used. In Fig. 7 the invention is shown in the form of a bracket, wherein the two pin members H H' are connected at their outer ends, as at h, from which point they diverge outwardly and terminating in securing portions h'. On the sides of the pin are the insulating-blocks H H², conveniently of wood, the same being secured in position by having struck-up or otherwise-formed ledges h² h³ projecting from the sides of the different branches of the pin. By forcing the insulator onto the pin the diverging arms thereof are forced together and the spring effect of the construction shown in Fig. 1 is attained.

By the construction above described I am enabled to secure an insulator-pin to the support without puncturing or boring out the support, as is the case when a wooden pin is used. I also largely prevent the pin from becoming loose on the cross-arm.

The invention is also designed for application to various forms of arms or supports and can be of a shape to fit various angles. It is also apparent that in the art of manufacturing the pins can be made at a relatively small expense.

I desire to call particular attention to the arm having a channel in its under face, as I have found that such a construction enables the application of the pin, as above described, at any point on the arm and permits the application of the pin between two wires, its adjustment toward and from adjacent wires, and its removal without interfering with the adjacent wires. It is also apparent that an arm of less diameter than those now in use can be employed, thus doing away with a large amount of weight and superfluous timber.

Having thus described the invention, what is claimed as new, and desired to be secured by Letters Patent, is—

1. An insulator-pin consisting of two mem-

bers formed of yielding material normally spaced apart to be forced toward each other by the application of an insulator and having at their upper ends means for securing an insulator thereon, and at its lower ends means for securing the same to a support. 70

2. An insulator pin or bracket comprising two independent members having yielding portions and normally spaced apart means at the ends of the members for securing an insulator thereto, the lower ends of said members being projected outwardly and fashioned to embrace and be secured to a suitable support, substantially as described. 75

3. The combination with a support, of an insulator-pin embracing the support and having complementary portions spaced apart, threads on the outer ends of the members, 85 and an insulator secured on the threaded portions and serving to draw the members toward each other, substantially as described.

4. An insulator-pin comprising two independent members, with means for securing the members independently to a support, threaded extensions on the members, and an insulator on the threaded extensions normally tending to draw the members toward each other, substantially as described. 90

5. An insulator-pin comprising two independent spring members having their insulator-supporting ends arranged in proximity to each other but out of contact, and provided with threads for receiving and securing an insulator in place, substantially as described. 95

6. An insulator-pin comprising two members fashioned to embrace a support, and having insulator-carrying portions arranged so that upon the application of the insulator 105 the members will be secured to the support, substantially as described.

7. In an insulator-pin, the combination with an insulator, of a pin comprising two members fashioned to be forced into contact with the holding-support by the application of the insulator, substantially as described. 110

8. The combination with a channeled supporting-arm, of an insulator-pin having portions bent and engaging in the channel of the supporting arm, and means on the pin for supporting and carrying an insulator, substantially as described. 115

9. In an insulator-pin, the combination with two metallic members, of threaded blocks secured to the outer face of the members, and means for securing the members to a suitable support, substantially as described. 120

10. An insulator-pin comprising two yielding members normally spaced apart, and insulating-blocks secured to the members on the outer faces thereof, and with which the insulator is adapted to engage, substantially as described. 125

11. A metallic insulator-pin comprising two members arranged in opposite relation, having outwardly-projecting lower portions fashioned to engage a suitable support, and inclined upper ends having projections for en- 130

gaging and holding an insulator, substantially as described.

12. The combination with a supporting arm, of two pin-sections arranged to embrace the arm and having inclined upper portions normally spaced apart, and means on the upper portions for engaging and securing an insulator thereto, substantially as described. 5

13. The combination with a supporting arm, of an insulator-pin comprising two metallic members fashioned to engage a support, having their upper ends inclined and provided with suitable threaded portions, braces for the inclined portions, and a block interposed 10 between the threaded portions, substantially as described. 15

14. The combination with a supporting arm, of an insulator-pin comprising two metallic members fashioned to engage a support, 20 having their upper ends inclined and provided

with suitable threaded portions, and a block interposed between the threaded portions, substantially as described.

15. The combination with an insulator-pin, of projections thereon, and independent insulating-blocks on opposite sides of the pin held in place by the projections, substantially as described. 25

16. An insulator-pin comprising separated portions and having means for securing an insulator thereto, of an insulating-filler between the said portions, substantially as described. 30

In testimony whereof I affix my signature in presence of two witnesses.

ELBERT T. BAILY.
